UNITED STATES PATENT OFFICE.

CHARLES J. T. BURCEY, OF SYRACUSE, NEW YORK.

APPARATUS FOR MANUFACTURING CHARCOAL.

SPECIFICATION forming part of Letters Patent No. 701,145, dated May 27, 1902.

Application filed May 25, 1901. Serial No. 61,901. (No model.)

To all whom it may concern:

Be it known that I, CHARLES J. T. BURCEY, of Syracuse, in the county of Onondaga and State of New York, have invented a certain 5 new and useful Apparatus for Manufacturing Charcoal, of which the following is a specification.

My invention has for its object the production of an apparatus for manufacturing charcoal which is particularly simple in construction and efficient in operation; and it consists in the combination, construction, and arrangement of the component parts of an apparatus for the desired purpose, as hereinabove fully described, and pointed out in the claims.

In describing this invention reference is had to the accompanying drawings, forming part of this specification, in which like letters indicate corresponding parts in all the views.

Figures 1 and 2 are respectively top plan and side elevations, partly in section, of a preferable embodiment of my apparatus for manufacturing charcoal. Fig. 3 is a sectional view taken on line 3 3, Fig. 1.

The illustrated preferable embodiment of my apparatus comprises, essentially, one or more chambers A for receiving the wood to be treated, combustion-chambers B, one or more conduits C for conducting the liberated gases and vapors from the chambers A, a condenser D, communicating with the conduits C, a conduit E for receiving the products discharged from the condenser, and a gas-conduit F, communicating with the condenser and having branches discharging, respectively, into the receiving-chambers A and the combustion-chambers B.

The chambers A are provided with heat-conducting passages a a' a^2 a^3 , presently described, are of any desirable form, size, and construction, and any suitable number thereof may be employed, although I have here illustrated but two. Said chambers are each provided with openings and closures a^4 therefor, unnecessary to describe, which permit the entrance of the wood and the removal of the charcoal, and are also provided with openings a^5 in their side walls and closures therefor, also unnecessary to describe, which permit the entrance of a tool, as a bar, in or-

der that the attendant may determine as to whether or not the wood is sufficiently charred.

The interiors of the chambers A, which receive the wood to be charred, are substantially air-tight and do not communicate with the passages, presently described, for conducting the products of combustion from the combustion-chambers B.

The heat-conducting passages a extend vertically in substantially the central portions of the bases of the chambers A and are formed with closed upper ends, and the heat-conducting passages a' are arranged in the bases of the chambers A, extend substantially radially and horizontally from the passages a in proximity to portions of the interiors of the chambers A, substantially equidistant from each other, and are formed with radial inner ends a^6 , communicating with the passages a , laterally-extending intermediate portions a^7 , and radial outer ends a^8 , being thus of substantially zigzag form. The passages a^2 are also arranged at the bases of the chambers A, are substantially ring-shaped in form, and communicate with the outer ends of the passages a' , and the passages a^3 communicate with the passages a^2 and the outer ends of the passages a' , extend upwardly therefrom within the interiors of the chambers A, and are formed with outwardly-deflected upper ends a^9 , which project through the side walls of the receiving-chambers A and are provided with exits and closures therefor, unnecessary to describe herein. The parts of the passages a a' a^2 a^3 arranged in proximity to the different contiguous portions of the interiors of the receiving-chambers A are provided with inclosing walls for preventing the escape of the products of combustion from said passages into the interiors of the receiving-chambers.

The combustion-chambers B are of any desirable form, size, and construction and communicate with the main heat-conducting passages a for discharging thereinto the heated products of combustion, which pass in tortuous paths through the passages a a' a^2 a^3 and impart a maximum amount of heat to the wood within the chambers A.

In the preferable construction of my invention a single conduit C opens from the top of each receiving-chamber A, conducts the gases

and vapors driven off from the wood within the corresponding chamber A, and is provided with suitable means, as a valve *c*, for preventing the passage therethrough of said gases and vapors. The condenser D is also of any desirable form, size, and construction, being generally provided with an upper chamber *d*, connected to the conduits C, substantially upright passages *d'*, depending from the chamber *d*, and a lower chamber *d''*, communicating with the lower ends of the passages *d'*. Said condenser D is also provided with a substantially upright passage or chamber *d'''* for receiving a cooling fluid, as running water, and with an inlet and an outlet *d⁴* *d⁵*, communicating, respectively, with the lower and upper portions of said passage or chamber *d'''*.

As clearly seen in the drawings, the conduit E for receiving the products accumulating in the condenser is arranged in suitable proximity to said condenser and is provided with an inlet *e*, into which said products are discharged by an outlet-pipe *e'*, extending outwardly from the chamber *d''* of the condenser and provided with a branch exit-passage *e''*, having a suitable valve.

The gas-conduit F communicates with the outlet-pipe *e'*, rises upwardly therefrom, and is formed with branches *f* *f'*, which are provided with suitable valves and may discharge, respectively, into the chambers A and B. Said conduit F is formed with an enlargement or chamber *f''*, provided with a wire-gauze partition (not illustrated) and with an outlet *f'''*, having a valve.

In the operation of my invention the chambers A are alternately filled with the wood to be treated, the charring in one chamber being completed at the time the treatment of the wood in the other chamber is commenced. The products of combustion generated in the chambers B escape through the passages *a* *a'* *a''* *a'''* to the atmosphere without contacting with the wood and in transit impart sufficient heat to the wood to liberate the volatile elements therefrom and transform the wood to charcoal. During the charring of the wood the operator makes frequent tests by inserting bars through the openings in the side walls of the chambers A and striking the wood or charcoal, and in case he ascertains that the charring is not taking place uniformly he varies the treatment of the wood by closing the exits of a number of the heat-conducting passages *a³* corresponding to the wood treated to the greatest extent, whereupon all of the heat escaping through the passages *a* is conducted through the remaining heat-conducting passages *a³*. The gases and vapors driven off from the wood pass through the conduits C and the condenser D, and certain of said volatile products become condensed and flow through the outlet-pipe *e'* to the conduit E, by which they are conducted to any desired locality for recovery. When first treating the wood, a large amount of steam is expelled therefrom, forming water in the con-

denser, and this water is usually permitted to escape through the branch exit-passage *e³* for preventing undue dilution of the products discharged into the conduit E. Certain of the gaseous products discharged into the condenser do not become liquid, but pass as a gas into the conduit F, whence they may be discharged into the chambers B and A, the gas being discharged into the chambers B for maintaining combustion therein and being discharged into the chambers A only after the wood is sufficiently charred and for the purpose of cooling the charcoal and preventing any combustion thereof. The enlargement or chamber *f²* of the conduit F collects any vapor passing through the conduit F and permits of the escape thereof, and the gauze partition of said chamber prevents the passage of the fire from the chambers B to the gases in the condenser.

The construction and operation of my apparatus will now be readily understood upon reference to the foregoing description and the accompanying drawings, and it will be particularly noted that more or less change may be made in the component parts thereof without departing from the spirit of my invention.

Having thus fully described my invention, what I claim as new, and desire to secure by Letters Patent, is—

1. An apparatus for manufacturing charcoal comprising a combustion-chamber, a receiving-chamber for the wood to be charred, a plurality of heat-conducting passages communicating with the combustion-chamber and arranged in proximity to different portions of the interior of the receiving-chamber, said passages being each provided with an inclosing wall for preventing the escape of the products of combustion from the passages into the interior of the receiving-chamber, and means for controlling the flow of the products of combustion from the combustion-chamber through said passages independently and thereby rendering substantially uniform the treatment of the wood in the different portions of the interior of the receiving-chamber.

2. An apparatus for manufacturing charcoal comprising a combustion-chamber, a receiving-chamber for the wood to be charred, a plurality of heat-conducting passages communicating with the combustion-chamber and arranged in proximity to portions of the interior of the receiving-chamber substantially equidistant from each other, said passages communicating independently with the atmosphere and being each provided with an inclosing wall for preventing the escape of the products of combustion from the passages into the interior of the receiving-chamber, and means for controlling the flow of the products of combustion from the combustion-chamber to the atmosphere through said passages independently and thereby rendering substantially uniform the treatment of the

wood in the different portions of the interior of the receiving-chamber.

3. An apparatus for manufacturing charcoal comprising a combustion-chamber, a receiving-chamber for the wood to be charred, a main heat-conducting passage communicating with the combustion-chamber, a plurality of passages communicating independently with the main heat-conducting passage and also communicating independently with the atmosphere, said passages being each provided with an inclosing wall for preventing the escape of the products of combustion from the passages into the interior of the receiving-chamber, and means for controlling the flow of the products of combustion from the combustion-chamber and the main heat-conducting passage to the atmosphere through said plurality of passages independently and thereby rendering substantially uniform the treatment of the wood in the different portions of the interior of the receiving-chamber.

4. An apparatus for manufacturing charcoal comprising a combustion-chamber, a receiving-chamber for the wood to be charred, said receiving-chamber being provided at its base with heat-conducting passages communicating with the combustion-chamber and arranged in proximity to different portions of the interior of the receiving-chamber and being provided with additional passages which communicate with the former passages and extend within the interior of the receiving-chamber and outwardly through the wall thereof, said former and additional passages being each provided with an inclosing wall for preventing the escape of the products of combustion from the passages into the interior of the receiving-chamber, and means for controlling the flow of the products of combustion from the combustion-chamber and the former passages through said additional passages independently and thereby rendering substantially uniform the treatment of the wood in the different portions of the interior of the receiving-chamber.

5. An apparatus for manufacturing charcoal comprising a combustion-chamber, a receiving-chamber for the wood to be charred, said receiving-chamber being provided at its base with a main heat-conducting passage communicating with the combustion-chamber, and a plurality of passages communicating with the main heat-conducting passage and leading therefrom in proximity to different portions of the interior of the receiving-chamber, and being provided with a plurality of additional passages which communicate with the former passages and extend within the interior of the receiving-chamber and outwardly through the wall thereof, said former and additional passages being each provided with an inclosing wall for preventing the escape of the products of combustion from the passages into the interior of the receiving-chamber, and means for controlling the flow of the products of combustion from

the combustion-chamber and the former passages through said additional passages independently and thereby rendering substantially uniform the treatment of the wood in the different portions of the interior of the receiving-chamber.

6. An apparatus for manufacturing charcoal comprising a receiving-chamber for the wood provided with a main heat-conducting passage, substantially horizontal heat-conducting passages formed in the base of the receiving-chamber and communicating with the main heat-conducting passage and extending outwardly therefrom, and additional heat-conducting passages communicating with the outer ends of the substantially horizontal heat-conducting passages and extending upwardly therefrom, said additional heat-conducting passages having their upper ends projected outwardly through the side walls of the receiving-chamber and provided with exits and closures therefor, and means for conducting the gases and vapors from the receiving-chamber, substantially as and for the purpose set forth.

7. An apparatus for manufacturing charcoal comprising a receiving-chamber for the wood provided with a main heat-conducting passage, substantially horizontal heat-conducting passages formed in the base of the receiving-chamber and communicating with the main heat-conducting passage and extending outwardly therefrom, a substantially ring-shaped heat-conducting passage communicating with the outer ends of the former passages, and additional heat-conducting passages communicating with the substantially ring-shaped heat-conducting passage and extending upwardly therefrom, said additional heat-conducting passages having their upper ends projected outwardly through the side walls of the receiving-chamber and provided with exits and closures therefor, and means for conducting the gases and vapors from the receiving-chamber, substantially as and for the purpose described.

8. An apparatus for manufacturing charcoal comprising a combustion-chamber, a receiving-chamber for the wood to be charred, a plurality of heat-conducting passages communicating with the combustion-chamber and arranged in proximity to different portions of the interior of the receiving-chamber, said passages being each provided with an inclosing wall for preventing the escape of the products of combustion from the passages into the interior of the receiving-chamber, means for controlling the flow of the products of combustion from the combustion-chamber through said passages independently and thereby rendering substantially uniform the treatment of the wood in the different portions of the interior of the receiving-chamber, a conduit for conducting the gases and vapors from the receiving-chamber, means for cooling the gases and vapors, and a conduit for conducting the

cooled gases from said means to the receiving-chamber and cooling the charcoal, substantially as described.

9. An apparatus for manufacturing charcoal comprising a combustion-chamber, a receiving-chamber for the wood to be charred, a plurality of heat-conducting passages communicating with the combustion-chamber and arranged in proximity to different portions 5 of the interior of the receiving-chamber, said passages being each provided with an inclosing wall for preventing the escape of the products of combustion from the passages into the interior of the receiving-chamber, means 10 for controlling the flow of the products of combustion from the combustion-chamber through said passages independently and thereby rendering substantially uniform the treatment of the wood in the different portions 15 of the interior of the receiving-chamber, a conduit for conducting the gases and vapors from the receiving-chamber, means for cooling the gases and vapors, and a conduit for conducting the cooled gases from said 20 means to the combustion-chamber, substantially as described.

10. An apparatus for manufacturing charcoal comprising a receiving-chamber for the wood provided with heat-conducting passages 30 at its base, a combustion-chamber communicating with the heat-conducting passages, a conduit for conducting the gases and vapors from the receiving-chamber, a condenser having a substantially upright passage for a cooling fluid provided with an inlet at its base 35 and an outlet at its top, and substantially upright passages communicating at their upper ends with the conduit, a second conduit,

means for conducting the condensed vapors and gases from the lower ends of the upright 40 passages therefor to the second conduit, and a gas-conduit communicating with said means and the combustion-chamber, and provided with a chamber containing a wire-gauze partition, substantially as and for the purpose 45 described.

11. An apparatus for manufacturing charcoal comprising a combustion-chamber, a receiving-chamber for the wood to be charred having a plurality of openings extending 50 through its inclosing walls and closures for said openings, a plurality of heat-conducting passages communicating with the combustion-chamber and arranged in proximity to different portions of the interior of the receiving-chamber, said passages being each provided with an inclosing wall for preventing the escape of the products of combustion from the passages into the interior of the receiving-chamber, and means for controlling 55 the flow of the products of combustion from the combustion-chamber through said passages independently and thereby rendering substantially uniform the treatment of the wood on the different portions of the interior 60 of the receiving-chamber.

In testimony whereof I have hereunto signed my name, in the presence of two attesting witnesses, at Syracuse, in the county of Onondaga, in the State of New York, this 10th 70 day of May, 1901.

CHARLES J. T. BURCEY.
